UNDERGARMENT

Henry Schoebel, Hempstead Gardens, Long Island, N. Y., assignor to Model Brassiere Co., Inc., Brooklyn, N. Y., a corporation of New York

Application February 9, 1935, Serial No. 5,711

3 Claims. (Cl. 2—36)

The invention relates to an article of apparel constituting an undergarment. Such undergarment may take the form of a girdle or a combination garment, which latter is a unitary garment including a brassière portion and a girdle. The invention consists in providing an adjunct for an undergarment of any usual type adapted to encircle the torso and more particularly that portion of such garment which overlies the abdominal region of the torso.

An object of the invention is to provide in such garment an elongated plate of a material of limited flexibility but of sufficient rigidity to maintain substantially its original shape and contour, such as a plate of steel which is of such configuration that in the position thereof in which it is secured to the undergarment, the plate overlies the hypogastric region of the body of the wearer of the garment so as to follow the anatomical contour of such abdominal region and be effective to control pressure against the body by the distribution of the flesh in such manner that the flesh is primarily lifted by the plate instead of being merely pressed inwardly thereby.

A more particular object of the invention is to provide a substantially rigid insert in an undergarment, in the portion thereof adapted to overlie the abdominal region when the garment is worn, for the purpose of reducing the waistline by the effective control of the flesh in such abdominal region through a distribution of the flesh in the immediate vicinity of the position of the insert, uniformly throughout such portion of the body.

A still further object of the invention is to provide such an insert of a configuration which will be most effective to attain the primary object, i. e., the lifting of the flesh which the insert is adapted to overlie without appreciable pressure thereof inwardly and to incorporate in such insert features which make it particularly effective in rounding the portions of the abdomen immediately adjacent the portion thereof which the insert is adapted to overlie when the garment is worn and to overcome the tendency of the flesh to mass on either side of the portion of the abdomen which the insert overlies. These two latter features consist in providing the plate with a concaved upper extremity and with inwardly curving side portions so that the insert as a whole constitutes a cup or receptacle within which is maintained the fleshy portion of the abdominal region which the plate is designed to overlie when the garment is worn.

In accordance with the invention the metal

plate or insert is made as narrow as possible, the width thereof being governed by the extent of the fleshy area which it is desired to control. The particular width of the metal insert for any particular undergarment is thus governed by the degree of correction from the central point of control desired to be attained and may most easily be determined by simple experiment by trying on a garment. A narrower insert than that necessary for absolutely corrective control of pressure against the body would not attain the objects of my invention as the massing of the flesh on either side of the insert would not thus be prevented. A wider insert than that dictated by the particular corrective measure to be taken would have no further effect than that obtained by the approximate width of the insert deemed desirable by trial.

A specific embodiment of my invention is illustrated in the accompanying drawings, the invention being shown as applied to a ladies' undergarment of the type known in the art as a "girdle", the drawings showing the specific embodiment by way of illustration rather than by way of limitation. In such drawings Fig. 1 is a front view of a girdle with my novel insert applied thereto; Fig. 2 is a section on the line 2, 2 of Fig. 1; Fig. 3 shows the girdle with my novel insert therein in position upon the body; Fig. 4 is a section on the line 4, 4 of Fig. 2 showing the front section of the girdle in rear elevation; Fig. 5 is an elevation of my novel insert; Fig. 6 is a side view of such insert; and Fig. 7 is a top view of the insert.

Referring more particularly to the drawings in which similar reference characters identify similar parts in the several views, the girdle embodying my invention preferably consists of a front section 10 and a rear section 11, these two sections being joined at one side of the garment throughout substantially one-half their length, the upper halves of the edges of the sections being provided, as is customary in the art, with fastener elements 12.

The front section 10 of the garment is constructed of any suitable material, for instance, silk brocade, and may include devices such as the elastic insert 13, adapting this section to particularly perform conforming functions in enclosing the figure of the wearer. The section 10 may be also provided with hose supporters 14 of conventional form.

The rear section of the girdle may be made entirely of an elastic material as illustrated in Fig. 1 or may be substantially of the form and mate-

rial shown as constituting the front section 10. Conventional hose supporters 15, 15 may depend from the rear section of the girdle.

The particular portion of the undergarment to which my invention relates is the upper portion 5 of the front section 10 which, when the garment is worn, overlies the abdominal region of the body of the wearer and, more particularly, the hypogastric portion of such abdominal region.

10 Such portion of the undergarment is constituted, as shown in Fig. 2, of the fabric layer comprising the upper portion of the girdle section 10 and a separate section 16 depending from the upper edge of the girdle proper. Such separate sec-

15 tion 16 consists of a strip of lining 17 and a second strip of lining 18, between which strips is positioned an elongated metal plate 19. In the illustrated embodiment, between the plate 19 and the inner lining strip 17 is positioned a flannel strip 20. The purpose of providing this flannel 20 strip is to prevent the hard surface of the metal plate from bearing against the body of the wearer through the lining 17, and affording the flannel a cushioning for such metal plate. While in the

25 specific embodiment illustrated I have shown a flannel strip as applied only to one side of the elongated metal plate, i. e. that side of such plate which is nearest the body of the wearer, it is within the contemplation of my invention to provide such flannel strip on both sides of the metallic plate so as to increase the cushioning thereof. Preferably the flannel strips 20 should be made 30 somewhat larger than the area of the plate. For instance, in the specific embodiment illustrated,

35 I have found that if I make the flannel strip of such a size as to extend approximately one-half inch beyond the periphery of the plate, and depend approximately one inch below the lower extremity of the plate, a particularly effective cushioning of the plate is obtained. Making the flannel strips of slightly larger area than that of the metal insert may also be of advantage in that when the garment is laundered, the flannel strip may shrink to some extent, but will still be of 40 larger area than the insert, so that the full cushioning effect of the flannel strip, by having the peripheral edges of the metal insert bear against such flannel strips, is retained even after repeated laundering of the garment.

45 50 As illustrated more particularly in Fig. 4, the metallic strip constituting the insert 19 is secured within and between the linings 17 and 18 by a line of stitching 21 following closely the periphery of the metallic insert 19.

55 The specific configuration of the metal insert 19 is shown in Figs. 5 to 7. It will be seen from such figures that the metallic insert is curved throughout its width near its upper end, as shown at 22, the edges of the plate as at 23, 23 being 60 curved to a greater extent than is the body portion of the plate.

The portion of the plate contiguous its lower extremity is curved inwardly, as shown at 24, the curvature of such portion of the plate being such 65 that the plate in its position within the garment and when the garment is worn, follows the contour of the body of the wearer at the lower portion of the abdominal region.

70 It will thus be seen that the metallic insert is characterized by three separate features of curvature. The most important of these features is the curvature of the bottom portion of the plate, as it is this particular configuration of the insert which makes possible the attainment of the primary corrective results sought by my novel construction.

When a garment, in which my inventive structure has been incorporated, is worn, this curved lower portion of the metallic insert is positioned so as to overlie the lower portion of the hypogastric region where there is usually an abnormal accumulation of flesh, the curvature of the plate being effective to lift, by means of the tilted extremity of such plate, the flesh without appreciable pressure thereof inwardly. Thus, a means of controlling the pressure against the body, which would result by the application of a flat plate against this portion of the body, is supplied without any pressure whatsoever against the body, the control being attained by lifting the fleshy portion of the body rather than pressing the same inwardly.

75 The second feature of my novel insert, namely that of the curvature of the upper portion thereof, prevents undue pressure of the sides of the plate against the body, the curvature being substantially identical with the curvature of the body of the wearer in the abdominal region which the upper portion of the plate is designed to overlie when the garment is worn.

20 25 The curvature of the edges of the insert is designed to overcome the massing of the flesh on each side of the plate. The curved edges of the insert prevent an abrupt elevation of flesh on each side of the insert and are effective to cause such a gradual rising of the flesh at the portions of the abdomen adjacent the position of the insert that a natural contour and rounding of the abdominal flesh conforming to the curvature of the body, upon each side of the insert, is secured. This curvature of the edges of the insert 30 completes, with the curvature of the upper portion of the plate and the curvature at the bottom extremity thereof, the cup or receptacle with 35 in which the abdominal region which the plate is adapted to overlie, is confined.

40 45 The advantages of my metallic insert, when applied to an undergarment of the type described, will be readily apparent to those skilled in the art, not only as a corrective measure for controlling pressure against the body of the wearer of the garment, but as a means of conforming the necessity of wearing an undergarment of the girdle or combination type with present trends of fashion. It is a well recognized fact that modern fashion dictates a tight and closely fitting 50 dress. The adoption of my novel construction will make possible the designing of even closer fitting dresses as the wearer whose body is encircled by a garment to which my novel metallic insert has been applied, will be enabled to carry out any bodily movement without disarrangement of any portion of the dress, particularly in the abdominal region. In other words, the wearer of my novel undergarment is able to assume any 55 posture without fear of presenting an unsightly 60 appearance, particularly when wearing a close-fitting dress.

65 70 The preferred material of which my novel insert is to be made is steel, preferably a steel that will resist corrosion, or material which has been plated to render it rustproof. I have found that the type known as "Swedish" steel is particularly suitable as it has a limited amount of flexibility but sufficient rigidity to maintain substantially its original shape and contour. Obviously, 75 any suitable material, for instance, celluloid, bone, ivory, or composition material such as a phenolic condensation product may be used in manufacturing my novel insert.

I claim:

1. An undergarment having an elongated plate of a material of limited flexibility but of sufficient rigidity to maintain substantially its original shape and contour, said plate being of substantial width and being secured to the undergarment in a portion thereof overlying the hypogastric region of the body of the wearer, said plate having a curved portion contiguous its lower extremity, the curvature of said portion being inward and substantially identical with the contour of the part of the body against which it rests, said plate having the upper portion thereof slightly concaved on its inner surface.
- 15 2. An undergarment having an elongated plate of substantial width and of a material of limited flexibility but of sufficient rigidity to maintain substantially its original shape and contour, said plate being secured to the undergarment in a portion thereof overlying the hypogastric region of the body of the wearer, said plate having a curved portion contiguous its lower extremity, the curvature of said portion being inward and substantially identical with the contour of the part of the body against which it rests, said plate having the upper portion thereof slightly concaved on its inner surface, the side edges of said plate being curved inwardly, the three features of curvature of said plate cooperating to constitute said plate a natural receptacle within which the abdominal region, which the plate overlies when the garment is worn, is confined.

the body against which it rests, the side edges of said plate being curved inwardly to conform to the curvature of the body and to lend rigidity to the plate.

3. An undergarment having an elongated plate of substantial width and of a material of limited flexibility but of sufficient rigidity to maintain substantially its original shape and contour, said plate being secured to the undergarment in a portion thereof overlying the hypogastric region of the body of the wearer, said plate having a curved portion contiguous its lower extremity, the curvature of said portion being inward and substantially identical with the contour of the part of the body against which it rests, said plate having the upper portion thereof slightly concaved on its inner surface, 15 the side edges of said plate being curved inwardly, the three features of curvature of said plate cooperating to constitute said plate a natural receptacle within which the abdominal region, which the plate overlies when the garment is worn, is confined.

HENRY SCHOEBEL.
